(57) **CLAIM**

The ornamental design for a lighting fixture, as shown and described.

DESCRIPTION

FIG. 1 is a front left perspective view from below of a lighting fixture according to the new design;

FIG. 2 is a rear right perspective view from above thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top view thereof; and,

FIG. 8 is a bottom view thereof.

The broken lines in the drawings illustrate portions of the lighting fixture that form no part of the claimed design.

The stippling shown in the figures represent translucent surfaces of the design and does not represent texture or surface ornamentation.

The breakaway lines in the figures indicate a symbolic break in the claimed design. The appearance of any portion of the design between the break lines forms no part of the claimed design.

The long dash-short dash lines in the drawings represent a boundary of the claimed design and form no part of the claimed design.
